(57) **CLAIM**

The ornamental design for a pop-up support for an electronic device protector, as shown and described.

DESCRIPTION

FIG. 1 is rear perspective view of our support design associated with a pop-up support for an electronic device protector showing the protector in closed configuration with the support in a deployed position. The protector is shown in broken line and is included to illustrate the environment of support design.

FIG. 2 is a left side view of the support design of FIG. 1. FIG. 3 is a right side view of the support design of FIG. 1. FIG. 4 is a rear view of the support design of FIG. 1; and, FIG. 5 is a top view of that portion of the support design that is visible from directly above the protector. The support design is not visible from the bottom or front of the protector. Portions of the protector in broken line are not claimed.
